SAFETY RAZOR

Filed June 13, 1930

Fig. 6.

UNITED STATES PATENT OFFICE

WILLIAM HARMAN BLACK, OF NEW YORK, N. Y.

SAFETY-RAZOR

Application filed June 13, 1930. Serial No. 460,973.

The invention comprehends a safety razor which may be quickly and readily cleaned after using without taking the safety razor apart.

5 The invention further comprehends a safety razor, the parts of which may be quickly and readily disassembled and assembled by the user without danger of the user cutting his fingers or hand.

10 The invention further comprehends a safety razor having an opening through which air may be blown to remove moisture or foreign matter which may cling to the razor or the razor blade.

15 The invention further comprehends a safety razor having a hollow post with lateral openings so that when the clamping plate is spaced from the guard plate of the safety razor air may be blown through the hollow post and out of the lateral openings to remove moisture and foreign matter from a razor blade disposed between the plates, as well as from the plates.

20 The invention furthermore comprehends a safety razor having means to secure a clamping plate relatively to a guard plate with a razor blade therebetween, which will prevent unexpected slipping of the parts relatively to each other.

25 Additional objects of the invention will appear in the following specification in which the preferred form of the invention is described.

30 In the drawings similar reference characters refer to similar parts in all the views, of which

Figure 1 is an end elevation of the safety razor,

35 Figure 2 is a sectional view on the line 2—2 of Figure 1,

40 Figure 3 is a sectional view on the line 3—3 of Figure 2,

Figure 4 is a sectional view on the line 4—4 of Figure 2,

45 Figure 5 is a perspective view illustrating the clamping plate with the hollow post and showing the outlet openings in the hollow post,

50 Figure 6 is a side elevation of the auxiliary hollow post which serves to hold the hollow

post with the clamping plate relatively to the sleeve with the guard plate, and

Figure 7 is a view illustrating a modified form of the invention.

By referring to the drawings it will be seen 55 that the clamping plate or member 10 has a hollow post 11 with two sets of outlet openings, one set of the outlet openings being referred to by the reference character 12 and extending downwardly and outwardly, and the 60 other set of outlet openings being referred to by the reference character 13 and extending upwardly and outwardly. The drawings show four outlet openings 12 and four outlet openings 13, but it will be understood that 65 one, two or more outlet openings 12 and one, two or more outlet openings 13 may be employed, as may be deemed expedient.

The hollow post 11 is disposed in a sleeve 14, a guard member or plate 15 being secured 70 to this sleeve 14, as best illustrated in Figure 3 of the drawings, and a razor blade 16 being disposed between the clamping plate 10 and the guard plate 15 in the customary manner.

The hollow post 11 is threaded and preferably this thread is an inner thread, as shown at 17, an auxiliary hollow post 18 having an outer thread 19 meshing with the inner thread 17 in the hollow post 11. This auxiliary hollow post 18 has at its outer end an outwardly 80 extending shoulder 20 engaging the outer end of the sleeve 14, the said shoulder 20 forming a part of the enlarged end 21 of the auxiliary hollow post 18, which has a milled outer surface which may be readily gripped between 85 the fingers so that the auxiliary hollow post 18 may be rotated relatively to the hollow post 11 to press the sleeve 14 with its guard plate 15 in the direction of the clamping plate 10.

It will be understood that the razor blade 16 may be mounted on the hollow post 11 with the studs 23 on the clamping plate 10 extending through the openings 24 in the razor blade. This may be readily done and the hollow post 11 may then be inserted in the sleeve 14, after which the auxiliary hollow post 18 may be rotated to lock the auxiliary hollow post 18 relatively to the hollow post 11 and to press the sleeve 14 downwardly so that 100

the guard plate 15 will press the razor blade 16 into position where the razor blade will be locked. It will be seen that there is practically no danger of the user cutting his fingers inasmuch as it is merely necessary to dispose the razor blade on the clamping plate 10 when the razor blade may be locked in position without the user touching the razor blade, the clamping plate 10 or the guard plate 15.

10 When the user has shaved and when he is desirous of cleansing the razor the auxiliary hollow post 18 is rotated relatively to the sleeve 14 by the means provided, which will rotate the auxiliary hollow post 18 relatively 15 to the hollow post 11 and in this way permit the razor blade 16 to assume a position relatively to the clamping plate 10, as illustrated in Figure 3 of the drawings, when the guard plate 15 may be moved from above. When 20 this has been done, it will be seen by referring to Figure 3 of the drawings, that the blade will assume a position substantially medially of the outlets 12 and 13 which latter will direct a column of air forced through the auxiliary hollow post 18 and the hollow post 11 against the upper and lower sides of the razor blade. This air may be blown through the auxiliary hollow post 18 and the hollow post 25 11 by the user and the air will serve to remove 30 foreign matter and moisture which may remain on the razor blade, the clamping plate and the guard plate after the parts have been washed under the faucet. When this has 35 been done the auxiliary hollow post 18 may be again turned home to clamp the sleeve 14 with the guard plate 15 against the razor blade 16 and in close proximity to the clamping plate 10.

It will be seen by referring to Figures 2 40 and 3 of the drawings that the bottom 25 of the opening in the hollow post 11 has sides that diverge upwardly to direct the air current to the outlets 13. It will also be seen by referring to Figure 1 of the drawings that the 45 sleeve is milled to assist in handling.

In the modified form of the invention illustrated in Figure 7 of the drawings, the hollow post 26 has an external thread which meshes with the inner thread on the sleeve 27, 50 the clamping plate 10 being secured to the hollow post 26 and the guard plate having an opening 28 through which the hollow post 26 is disposed. The sleeve 27 may be rotated relatively to the hollow post 26 and the clamping plate 10, which will press the sleeve 27 55 against the guard plate 15 to lock the razor blade 16 between the clamping plate 10 and the guard plate 15. In other respects the construction disclosed in Figure 7 of the drawings corresponds with the construction shown 60 in the other figures.

What is claimed is:

1. A razor having a hollow post and two plates, the hollow post having two converging outlets for directing air currents to oppo-

site sides of a razor blade normally disposed between the plates.

2. A razor having a hollow post and two plates, the hollow post having two converging outlets for directing air currents to opposite sides of a razor blade normally disposed between the plates, and means in the hollow post for directing the air to one of the outlets. 70

3. A razor having two curved substantially parallel plates for curving and clamping a razor blade therebetween, a sleeve on one of the plates, and a hollow post on the other plate disposed in the sleeve, the hollow post having one or more outlets, all of which are normally closed by the sleeve, the outlet being 75 opened by a movement of the sleeve with its plate so that a fluid may be directed through the outlet to a razor blade disposed between the plates. 80

4. A razor having a sleeve with a plate mounted thereon, a hollow post disposed in the sleeve with a companion plate, the hollow post being provided with one or more outlets, all of which are positioned adjacent a plate to direct an air current against the surface or surfaces of a razor blade, and means for securing the hollow post and the sleeve relatively to each other. 85

5. A razor having a sleeve with a plate mounted thereon, a hollow post disposed in the sleeve with a companion plate, the hollow post being provided with one or more outlets, all of which are positioned adjacent one of the plates to direct an air current against a surface or surfaces of a razor blade, the hollow post being provided with a threaded portion and a hollow threaded member meshing with the thread on the post and engaging the sleeve for holding the plates relatively to each other. 90

Signed at New York city, in the county of New York and State of New York, this 11th day of June, 1930, A. D.

WILLIAM HARMAN BLACK.
